DETACHABLE BASE STAPLING MACHINE

William G. Pankonin, Chicago, Ill., assignor to Triangle Tool & Manufacturing Company, Chicago, Ill., a corporation of Illinois

Application January 25, 1955, Serial No. 483,867

4 Claims. (Cl. 1-3)

This invention relates to improvements in desk type stapling machines having the staple driving mechanism detachable from the base for use as a tacker.

Stapling machines of this type are shown in William G. Pankonin Patents 2,056,480 for Stapling Device issued October 6, 1936, and 2,059,021 for Stapling Machine issued October 27, 1938. The detaching means of the first mentioned patent is not readily discernible to the average user of the stapling machine and hence this usage of the machine is often forgotten. Such means also requires careful registration for reassembly. The detaching means of the second mentioned patent does not provide a sufficiently positive position to maintain the essential accurate alinement between the driving blade of the staple driving mechanism and the clinching anvil on the base.

It is the object of this invention, therefore, to provide an easily discernible, simply operated, positive alining means for detachably mounting the staple driving mechanism to the base, which is also inexpensive to manufacture.

To accomplish this, a mounting member is permanently pivoted to the base for limited movement with respect thereto. Such member is spring biased to maintain the staple driving mechanism in raised position. Elements on such member and mechanism interengage to provide positive alinement of the mechanism with such permanent pivot and a frictional lock holds said mechanism in such positive position. Disengagement is accomplished by merely swinging the staple driving mechanism up beyond the upper limit of the swing of said member. This separates both the frictional lock and alining elements. Reengagement is accomplished by seating one set of such elements and swinging the locking mechanism down to the lower limit of said member. This cams in the other set of elements to make positive alinement and engages the frictional lock to maintain such alinement during normal use as a staple driving and clinching mechanism.

The features of the invention which are considered new and useful and, therefore, patentable are set forth in the claims below. The details of an embodiment of the invention can best be understood from the following specification and the drawings, in which:

Fig. 1 is a view in side elevation of a stapling machine embodying the present invention;

Fig. 2 is an enlarged fragmentary top plan view of the means for detachably mounting the staple driving mechanism to the anvil carrying base;

Fig. 3 is an enlarged fragmentary top plan view similar to that shown in Fig. 2 with the staple driving mechanism removed;

Fig. 4 is an enlarged fragmentary sectional view taken on the line 4-4 of Fig. 1;

Fig. 5 is an enlarged fragmentary sectional view taken on the line 5-5 of Fig. 1;

Fig. 6 is an enlarged fragmentary sectional view taken on the line 6-6 of Fig. 1; and

Fig. 7 is a fragmentary view in side elevation showing the staple driving mechanism disengaged from the sup-

2

porting base, parts being shown in section for clarity in illustration.

The invention shown in the drawings is incorporated in a stapling machine of usual design including an anvil carrying base 10 to which the staple driving mechanism 12 is pivotally mounted when the machine is used to drive staples through material and clinch the legs of such staples. The staple driving blade must be maintained in close alinement with clinching cavities in the anvil or improper functioning will result. It is also desirable to resiliently hold the driving mechanism raised as shown in Fig. 1 to permit ready insertion of material to be stapled. To accomplish these purposes, elongated sides 14 of the magazine of the driving mechanism are temporarily locked between sides 16 of a mounting member 18 permanently pivoted to the base 10. The sides 16 are interconnected and held by two spaced braces 19 and 21 transversely extending between the lower edges of such sides and make a rigid open top receptacle. The mounting member 18 is permanently pivoted between wings 20 struck up from the base 10 by a pin 22 secured to such wings and passing through holes 24 in tabs 26 depending from the sides 16.

The upward movement (counter-clockwise as viewed in Figs. 1 and 7) of member 18 is limited by the engagement between its left lower corner and the top of the base 10 to an angle of about 25° from the base. The member 18 is normally resiliently held with its right end spaced from the base, as shown in Figs. 1 and 7, by a riser 28 pivoted on the pin 22 and swingable within the limits created by the positioning of the sides of a notch 30 on opposite sides of the base 10 (see Fig. 7). Lateral displacement of such riser may be restrained by projections 32 which overlap the sides of the riser 28. A coiled compression spring 34 held by centering fingers 36 and 38 on the base and riser resiliently maintains the riser in such raised position.

The sides 14 of the staple driving mechanism have rearwardly and upwardly opening notches 40 into which will slide studs 42 projecting inwardly from the sides 16 as the staple driving mechanism 12 is moved longitudinally in between the sides 16 while tilted at an angle, in the neighborhood of 45°, with respect to the base. No accuracy is needed to make this jointure fit. The left lower corners of the sides 14 will be guided by the brace 19 so that the openings to the notches 40 will be automatically alined with the studs 42. Additional guiding may be obtained by providing slopes 44 on the ends of the sides 14 from which the notches 40 recede.

With the notches 40 fully seated on the studs 42, the staple driving mechanism is swung clockwise downwardly with respect to the member 18 until pimples 46 on the inner surfaces of the sides 16 near the front (right) ends thereof frictionally seat in holes 48 in the side 16. The frictional engagement thus established will be sufficient to lock the staple driving mechanism 12 in the mounting member 18 so that such mechanism will be guided by such member with the staple driver in alinement with the clinching anvil.

In order to assist in seating the pimples 46 in the holes 48 and also to assure positive alinement between mechanism and holding member, the sides 14 have downwardly opening notches 50, the mouths of which straddle studs 52 on the inner faces of the sides 16 as the mechanism is swung downwardly in the seating action. Such engagement positively longitudinally alines the sides 14 with the sides 16 and hence insures that the staple driving mechanism will always seat in the same relationship to the pivot 32 and remain in proper alinement with the anvil. The rear edges (left) of the notches 50 may be convexly curved about the center of the circular end of the notches 40 thus providing with the notches 40 proper

camming surfaces which closely and positively engage the spaced studs from opposite directions. Any inaccuracy in the fit between the pimples 46 and holes 48 (which fit is difficult to control) will not result in any misalignment and such pimples and holes are used mainly to provide a temporary lock maintaining joint angular movement between the stapling mechanism and the mounting member. While not essential except for conserving vertical height, cut-outs 54 may be provided in the bottom and sides 14 to accommodate the pin 22.

In order to disengage the staple driving mechanism 12 from the base 10, it is only necessary to swing such mechanism upwardly (counter-clockwise) until the mounting member 18 reaches its upper limit, further upward movement will disengage the lock between the pimples 46 and the holes 48 and permit the sides 14 to be swung clear of the sides 16 separating the engagement between the notches 50 and studs 52 and notches 49 and studs 42.

I claim:

1. A desk type stapling machine having a base, a mounting member pivoted to said base and having limited pivotal movement with respect thereto, resilient means for urging said mounting member to a raised position with respect to such base between said limits, a staple magazine having a portion interfitting with said mounting member, staple driving mechanism carried by said magazine, spaced locking elements on said mounting member swingable therewith about the pivot of said mounting member, and angularly spaced locking elements on said portion cooperative with said spaced locking elements to properly align said staple driving mechanism with said mounting member and maintain said mechanism in frictional engagement as so aligned.

2. Detachable means for pivotally mounting a staple driving mechanism and a staple magazine to a base, comprising a mounting member pivoted to said base, a locking element adjacent one end of said mounting member, a complementary locking element on the outer end of said staple magazine engageable with said locking element upon endwise movement of said staple magazine angularly downward toward said mounting member, a frictionally engageable locking element near the other end of said

mounting member, and a frictional locking element on said staple magazine engageable with said frictional locking element when said magazine is properly seated in said mounting member.

5. Detachable means for pivotally mounting a staple driving mechanism and a staple magazine to a base, comprising a mounting member pivoted to said base, a locking element adjacent one end of said mounting member, a complementary locking element on the outer end of said staple magazine engageable with said locking element, a slope on the end of said staple magazine which upon endwise movement of said staple magazine angularly downward toward said mounting member guides said locking elements into engagement, a frictionally engageable locking element near the other end of said mounting member, and a frictional locking element on said stapling magazine engageable with said frictional locking element when said magazine is properly seated in said mounting member.
- 10 6. In a stapling machine of the type having staple driving mechanism including a magazine detachably removable from a base with which said mechanism has relative pivotal motion, mounting means comprising a member pivotally secured to said base, spaced locking elements 25 on said member, spaced locking elements on said stapling driving mechanism cooperative with said locking elements, said elements arranged in spaced pairs of a cooperative notch and stud, the notch and stud of one pair being engageable upon linear movement of said staple mechanism 30 relative to said mounting member, and the notch and stud of the other pair being engageable upon angular movement of said stapling mechanism with respect to said mounting member about said pair.
